United States Patent Office

Des. 204,935
Patented May 31, 1966

204,935

BRASSIERE

Charles M. Sachs, West Englewood, N.J., assignor to International Latex Corporation, Playtex Park, Dover, Del., a corporation of Delaware

Filed Sept. 14, 1964, Ser. No. 81,719

Term of patent 14 years

(Cl. D20—4)

The essential features of my design reside in the full line disclosure on the drawing.

I claim:

The ornamental design for a brassiere, as shown and described.
